CLAIM

The ornamental design for a clogging dance tap device, as shown and described.

DESCRIPTION

FIG. 1 is a bottom and left front perspective view of a clogging dance tap device showing my new design;
FIG. 2 is a top and left front perspective view thereof;
FIG. 3 is a front elevational view of FIG. 1;
FIG. 4 is a rear elevational view of FIG. 1;
FIG. 5 is a right side elevational view of FIG. 1, the left side thereof, being a mirror image hereto.
